UNITED STATES PATENT OFFICE.

JOHN ALLEN CLARK, OF COLUMBUS, OHIO.

STRAINER.

1,000,072.

Specification of Letters Patent. Patented Aug. 8, 1911.

Application filed August 6, 1910. Serial No. 575,960.

To all whom it may concern:

Be it known that I, JOHN ALLEN CLARK, a citizen of the United States, residing at Columbus, in the county of Franklin and

5 State of Ohio, have invented a new and useful Strainer for Straining Fruit-Juices and other Liquids.

The present invention relates to improvements in strainers for domestic or household 10 purposes, and is especially adapted for use in straining the syrup from fruits, etc. In devices of this character cleanliness and durability are essential characteristics, and the object of my invention is to combine 15 these features in a contrivance which is also simple in construction and comparatively cheap in first cost.

The invention consists essentially in a supporting or suspending device combined with 20 and adapted for use with one or more straining receptacles, and it further consists in certain novel features of construction and combinations and arrangements of parts as will be hereinafter more fully set forth.

25 In the accompanying drawings I have illustrated one example of the physical embodiment of my invention constructed according to the best mode I have so far devised for the practical application of the 30 principle thereof.

Figure 1 is a plan view of the suspending ring and its accessories. Fig. 2 is a partial sectional view of Fig. 1 illustrating two straining receptacles suspended from the 35 ring. Fig. 3 is a detail view of a snap or clamp ring by which the straining receptacle is suspended, and Fig. 4 illustrates the device in use.

The device comprises a suspending ring 1 40 which is preferably of metal and formed U-shape in cross section, thus providing an annular groove and an outer and inner flange thereabout. At diametrically opposite points the ring 1 is provided with integral 45 flattened projections which are riveted, respectively, to the handle 1^a and supporting arm 1^b. The handle and arm are also of metal, being preferably stamped from sheets, as is also the ring 1. The handle in addition to its inherent function, also, in combination with the arm forms two supporting points for the suspending ring when it is in use with the straining receptacles. The straining receptacles are attached to and are

suspended from the ring 1 by means of the 55 snap rings 2 and 3, and these receptacles 2^a and 3^a are preferably composed of textile fabric.

The snap rings 2 and 3 are similar in construction, but of different sizes or diameters, 60 and each is provided with a sleeve 2^b secured on and projecting from one end of the snap ring. The projecting portion of the sleeve forms a socket for the complementary end of the ring. The respective receptacles or 65 bags are stitched, at their top edges, over the snap rings, and when the rings are placed in the groove of the suspending ring 1 the bags 2^a and 3^a are suspended within the ring 1. I have illustrated two bags of 70 textile material, one, the inner, being of coarse mesh and the other being of comparatively finer mesh, and I find that the use of these two bags of differing texture facilitate the straining of fruits.

75 It will of course be understood that I may employ only one of the straining bags, or if necessary, additional bags may be utilized if desired, the groove in the ring 1 being of a size to accommodate several snap rings.

80 The elasticity of the snap rings enables the same to be placed in position in the grooved ring 1 or removed therefrom with facility, and when in use the socket 2^b holds the adjoining end of the ring against displacement.

85 From the above description taken in connection with the drawings, it is evident that I have provided a device which fulfills the conditions and purposes set forth as the object of my invention.

90 Having thus fully described my invention, what I claim as new and desire to secure by Letters Patent is:—

95 The combination with an open ring having outer and inner flanges forming an annular groove, and provided with a handle and a supporting arm, of a plurality of elastic rings held in said groove between said flanges, and straining receptacles secured to said elastic rings and suspended one 100 within another, the texture of said receptacles diminishing in mesh from the innermost receptacle.

JOHN ALLEN CLARK.
